UNITED STATES PATENT OFFICE.

KARL A. STAHLGREN, OF NEWPORT, RHODE ISLAND.

HYDROCARBON-BURNER.

1,341,524.

Specification of Letters Patent. Patented May 25, 1920.

Application filed November 26, 1919. Serial No. 340,765.

To all whom it may concern:

Be it known that I, KARL A. STAHLGREN, a citizen of the United States, and a resident of Newport, in the county of Newport and State of Rhode Island, have invented a new and Improved Hydrocarbon-Burner, of which the following is a full, clear, and exact description.

The object of the invention is to provide 10 a new and improved hydrocarbon burner arranged to insure a thorough atomizing of the crude oil or other liquid hydrocarbon fuel, and to produce an effective mixing of the air and the atomized fuel to insure complete combustion thereby utilizing the liquid fuel to the fullest advantage.

Another object is to insure the formation of a conical shaped flame.

Another object is to provide a hydrocarbon burner which is simple and durable in construction and composed of comparatively few parts, not liable to become disarranged during the use of the burner or by the heat incident to the burning fuel.

25 With these and other objects in view, the invention consists of certain novel features of construction as hereinafter shown and described and then specifically pointed out in the claims.

30 A practical embodiment of the invention is represented in the accompanying drawings forming a part of this specification, in which similar characters of reference indicate corresponding parts in all the views.

35 Figure 1 is a longitudinal central section of the improved hydrocarbon burner, the section being on the line 1—1 of Fig. 2;

Fig. 2 is a cross section of the same on the line 2—2 of Fig. 1; and

40 Fig. 3 is a similar view of the same on the line 3—3 of Fig. 1.

On a suitably constructed frame 10 is mounted a motor 11, of any approved construction, and having its hollow shaft 12 connected by a coupling 13 with a hollow shaft 14 journaled in bearings 15 and 16, of which the bearing 15 is arranged in the inlet 17 of the casing 18 of a fan or a blower having its rotor 19 secured to the shaft 14.

45 The fan casing 18 is attached to the frame 10. The central outlet 20 of the fan casing 18 is provided with a tube 21 supporting at its forward end a nozzle 25 which supports the bearing 16 of the shaft 14. The latter extends centrally into the nozzle 25, and on the forward end of the shaft is se-

cured a centrifugal atomizer 30 in the form of a cup, forming with the nozzle 25 an annular air passage 31. Into the atomizer 30 discharges the forward end of a liquid fuel supply pipe 32 which extends through the hollow shafts 14 and 12 and connects with a supply pipe 33 extending from a tank or reservoir containing crude oil or other liquid fuel. The amount of liquid fuel passing to the pipe 32 is controlled by a suitable needle valve 34 arranged at the junction of the pipes 32 and 33.

The back of the atomizer 30 is provided with an auxiliary fan 40, the blades of which coat with the rear wall of the nozzle 25, and this auxiliary fan 40 receives the compressed air discharged by the main fan 19 and increases the pressure of this air and discharges the air through the annular passage 31 from the mouth of the nozzle located slightly in the rear of the front end of the atomizer 30, as plainly shown in Fig. 1.

It is understood that when the motor 11 is running, the atomizer 30 and the fans 19 and 40 are rotated in unison, and the liquid fuel passing from the supply pipe 32 into the atomizer 30 is thrown outwardly by centrifugal force from the forward end of the atomizer and there commingles with the compressed air passing out of the forward end of the nozzle 25. The compressed air deflects the atomized fuel and thoroughly commingles with the same to form a highly inflammable mixture to be burned in the furnace. It is also understood that the centrifugal action of the atomizer 30 is sufficiently great to insure a thorough atomizing of the liquid fuel, and the atomized fuel effectively commingles with the air under pressure discharged from the nozzle 25. It will further be noticed that by mounting the atomizer 30 and both fans 19 and 40 on the same shaft 14 a very simple construction is provided and one not liable to get easily out of order. By providing two fans 19 and 40 the desired air pressure is obtained without providing an unduly large single fan. In this connection it is understood that in practice the second fan 40 raises the air pressure about one ounce above the pressure obtained from the fan 19. By arranging the cup-shaped atomizer 30 and the nozzle 25 in the manner described, the inflammable mixture formed provides a conically shaped flame.

In order to insure the combustion of the

mixture of fuel and air, use is made of an air register 50 comprising a casing 51 attached to the wall 52 of the furnace and inclosing the nozzle 25 and the atomizer 30, 5 as plainly shown in Fig. 1. The casing 51 is provided with an air entrance chamber 53 of ring shape and open at its peripheral face. In this chamber 53 are arranged vanes 54 which give the air passing through 10 the chamber 53 to the casing 51 a rotary or whirling motion, thereby mixing it with the inflammable mixture formed by the compressed air and the atomized fuel which issues from the nozzle 25 and the atomizer 30, as above explained. In the rear of the chamber 53 is arranged a shutter 60 adapted to be moved forward or backward to decrease or increase the amount of air passing 15 from the entrance chamber 53 by way of the vanes 54 into the casing 51. The shutter 60 is attached to two horizontally extending rods 61 mounted to slide in suitable bearings 62 (see Fig. 2), arranged on the frame 10, and the said rods 61 are provided with racks 63 (see Figs. 1 and 3) in 20 mesh with segmental gear wheels 64 secured on a transversely extending shaft 65 journaled in bearings 66 mounted on the frame 10. A handle 70 is attached to the shaft 65 25 to permit the operator to turn the shaft 65 with a view to cause the segmental gear wheels 64 to actuate the racks 63 and consequently the rod 61 whereby the shutter 60 is moved forward or backward according to 30 the direction in which the handle 70 is moved at the time. The chamber 53 is preferably connected by a hinge 80 with a casing 51 and the frame 10 is preferably attached to the chamber 53 to permit of 35 swinging the chamber 53 into an open position thus carrying the frame 10 and the parts supported thereby along with a view to move the nozzle 25 and the atomizer 30 40 out of the casing 51.

Having thus described my invention, I claim as new and desire to secure by Letters Patent:—

1. A hydrocarbon burner, comprising an air discharge nozzle, a centrifugal atomizer 50 mounted to turn in the said nozzle and forming with the latter an annular passage for the air, main air pressure means connected with the said passage, and auxiliary air pressure means within the said passage to increase the pressure of the air delivered by the said main air pressure means and to discharge the increased air pressure through the nozzle to commingle with the atomized fuel discharged from the outer edge of the 55 said atomizer.

2. A hydrocarbon burner, comprising an air discharge nozzle, a centrifugal atomizer mounted to turn in the said nozzle and forming with the latter an annular passage for the air, main air pressure means connected 60

with the said passage, auxiliary air pressure means within said passage to increase the pressure of the air delivered by the said main air pressure means and to discharge the increased air pressure through the nozzle to commingle with the atomized fuel discharged from the outer edge of the said atomizer, and driving means common to the said main air pressure means and the said auxiliary air pressure means. 70

3. A hydrocarbon burner, comprising an air discharge nozzle, a centrifugal atomizer mounted to turn in the said nozzle, a main fan supplying air to the said nozzle, and an auxiliary fan in the said nozzle to increase 80 the pressure of the air delivered by the said main fan and to force the said air out of the nozzle.

4. A hydrocarbon burner, comprising a nozzle, a centrifugal atomizer mounted to 85 rotate within the said nozzle, a main fan having a casing provided with an outlet connected with the entrance of the said nozzle, an auxiliary fan forming part of the said centrifugal atomizer and coacting with 90 the said nozzle to increase the pressure of the air delivered by the said main fan to the said nozzle, and means common to both the said main fan and the said atomizer and its fan to rotate the same in unison. 95

5. A hydrocarbon burner, comprising a burner casing, a main fan wheel provided with a casing having its discharge connected with the inlet of the said burner casing, a burner mounted to turn in the said burner 10 casing and provided with an auxiliary fan wheel coacting with the burner casing to increase the pressure of the air delivered by the said main fan to the burner casing, and a driven shaft carrying the said main fan 10 wheel and the said burner.

6. A hydrocarbon burner, comprising a nozzle, a centrifugal atomizer mounted to rotate within the said nozzle, a main fan having a casing provided with an outlet 1 connected with the entrance of the said nozzle, an auxiliary fan forming part of the said centrifugal atomizer and coacting with the said nozzle to increase the pressure of the air delivered by the said main fan to the said nozzle, means common to both the said main fan and the said atomizer and its fan to rotate the same in unison, and an air supply register having a casing open at the front and housing the said nozzle and atomizer, the rear of the said register casing being provided with an air entrance chamber having deflecting vanes.

7. A hydrocarbon burner, comprising a nozzle, a centrifugal atomizer mounted to rotate within the said nozzle, a main fan having a casing provided with an outlet connected with the entrance of the said nozzle, an auxiliary fan forming part of the said centrifugal atomizer and coacting with

the said nozzle to increase the pressure of the air delivered by the said main fan to the said nozzle, means common to both the said main fan and the said atomizer and its fan to rotate the same in unison, an air supply register having a casing open at the front and housing the said nozzle and atom-
izer, the rear of the said register casing being provided with an air entrance chamber having deflecting vanes, and a shutter movable within the said air entrance chamber to control the amount of air passing into and through the register housing. 10
